To all whom it may concern:

Be it known that we, Warren A. Johnson and Ulman B. Peterson, citizens of the United States, residing in Arcadia and Pasadena, respectively, in the county of Los Angeles and State of California, have invented a new, original, and ornamental Design for a Sandwich Stand, of which the following is a specification, reference being had to the accompanying drawings, forming a part thereof.

We claim:

The ornamental design for a sandwich stand, substantially as shown.
